[57] CLAIM

I claim the ornamental design for a screwdriver handle, as shown and described.

DESCRIPTION

FIG. 1 is a perspective view of a screwdriver handle; FIG. 2 is a side view of the screwdriver handle, the side view at 180 degrees being identical; FIG. 3 is a bottom view of the screwdriver handle; FIG. 4 is a top view of the screwdriver handle; and, FIG. 5 is a side view 90 degrees to the view of FIG. 2 of the screwdriver handle, the side view at 180 degrees to FIG. 5 being identical.

The tool shaft depicted by means of broken lines in FIGS. 1, 2, and 5 have been shown for illustrative purposes only and forms no part of the claimed design.
